John Richard Morgan, Oak Park, Ill., assignor
to Birtman Electric Company, Chicago, Ill., a
corporation of Illinois

Application March 11, 1935, Serial No. 55,837

Term of patent 7 years

To all whom it may concern:

Be it known that I, John Richard Morgan, a subject of the King of Great Britain, residing at Oak Park, in the county of Cook and State of Illinois, have invented a new, original, and ornamental Design for a Casing for Vacuum Cleaner, of which the following is a specification, reference being had to the accompanying drawing, forming a part thereof, in which—

The figure is a perspective view of a casing for a vacuum cleaner showing my new design.

I claim:

The ornamental design for a casing for vacuum cleaner, as shown.

JOHN RICHARD MORGAN.
